CLAIM

The ornamental design for a headset for an electronic device, as shown and described.

DESCRIPTION

FIG. 1 is a front elevational view of a first embodiment of a headset for an electronic device showing my new design;

FIG. 2 is a top plan view thereof;

FIG. 3 is a first side elevational view thereof;

FIG. 4 is a bottom plan view thereof;

FIG. 5 is a side top rear perspective view thereof;

FIG. 6 is a rear elevational view thereof;

FIG. 7 is a rear side perspective view thereof;

FIG. 8 is a second side elevational view thereof, showing a view opposed to FIG. 3;

FIG. 9 is a front elevational view of a second embodiment of a headset for an electronic device showing my new design;

FIG. 10 is a top plan view thereof;

FIG. 11 is a first side elevational view thereof;

FIG. 12 is a bottom plan view thereof;

FIG. 13 is a side top rear perspective view thereof;

FIG. 14 is a rear elevational view thereof;

FIG. 15 is a rear side perspective view thereof; and,

FIG. 16 is a second side elevational view thereof, showing a view opposed to FIG. 11.
